INVENTOR.
THOMAS TALBOT
BY John E. Hubbell
ATTORNEYS.

UNITED STATES PATENT OFFICE

THOMAS TALBOT, OF SEDGLEY, NEAR DUDLEY, WORCESTER, ENGLAND, ASSIGNOR, BY MESNE ASSIGNMENTS, TO SWINDELL-DRESSLER CORPORATION, OF PITTSBURGH, PENNSYLVANIA, A CORPORATION OF PENNSYLVANIA

TUNNEL KILN

Application filed July 22, 1929. Serial No. 379,973.

My present invention relates in general to the construction and method of operation of continuous tunnel kilns of the type in which the goods or material being heat treated are progressively moved through one or more heating zones in the kiln and are afterward cooled while passing through a cooling zone, the goods passageway of which is generally a continuation of that of the last heating zone.

The object of my invention is to provide a kiln of the type referred to with an improved method of and means for abstracting heat from the goods and from the trucks or cars on which the goods are carried while in the cooling zone and effectively utilizing the heat abstracted for preheating air for combustion of the fuel in the heating zone and other purposes. Another object of my invention is to provide an improved arrangement and location of the fan mechanism, for circulating the cooling medium, which is preferably air drawn from the surrounding atmosphere. A further object of my invention is to provide an improved kiln construction and apparatus for maintaining predetermined thermal conditions in the cooling zone, and particularly in the portion of the cooling zone adjacent the heating zone.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of the invention.

40 Of the drawings:

Fig. 1 is a somewhat diagrammatic longitudinal elevation with parts broken away and in section of a portion of a kiln;

Fig. 2 is a plan view of the apparatus illustrated in Fig. 1 with parts broken away;

Fig. 3 is a transverse section on the line 3—3; and

Fig. 4 is a similar section on the line 4—4 of Fig. 1.

50 In the drawings I have illustrated the use

of my invention in a tunnel kiln of a well known type but having certain special features of construction due to the use therein of the present invention. As shown, the kiln comprises a horizontally elongated kiln chamber A enclosed by vertical side walls B of refractory masonry and insulated in any of the usual ways. The kiln is formed with the usual masonry benches C extending throughout the kiln chamber and located at opposite sides of the goods pathway. Kilns of this type comprise a heating or furnace zone *a* and a cooling zone *b* through which the goods to be treated are carried on cars which enter the kiln at the inlet end of the heating zone and pass successively through the heating and cooling zones, and are removed from the exit end of the latter. The inlet and exit ends of the kiln are provided with means permitting the insertion and removal, respectively, of the kiln cars without any appreciable entrance of air into, or escape of heating gases from, the kiln chamber.

In the heating zone, the kiln heating means may consist of elongated combustion chambers or muffles, fire boxes, or groups of gas or oil burners. While the specific form of heating means used forms no part of my present invention, I have illustrated a fuel supply conduit D having branch pipes D' leading to groups of fuel burners mounted in the side walls B in the heating zone.

The cooling zone *b* is divided into a short initial or high temperature section *b'* having the same external width as the heating zone and a main or low temperature section *b''* between the initial section *b'* and the exit end of the kiln. The main section has a kiln chamber width similar to that in the initial section but side walls of considerably less thickness than the latter, as shown in Figs. 3 and 4. As illustrated in Figs. 1 to 3, the cooling zone section *b''* is constructed with a hollow arch consisting of vertical wall sections F at the inner side of the walls B and an arched wall G of panel brick or similar material spaced from the wall sections F and the kiln crown A', sufficiently to form side and crown cavities H and J, respectively, therebetween. The crown cavity J opens at its

sides to the side cavities H. The side wall sections F are slightly spaced from the main side walls B and the space therebetween preferably filled with insulating material. The wall sections F are connected to the sides of the wall G by tie bricks E at spaced points, as shown in Fig. 3.

The wall cavity at each side of the section b² is divided into a series of end to end compartments H', H², H³, H⁴ by division walls K extending vertically between the corresponding arched wall G and the adjacent wall section F. The division walls extend across the kiln crown dividing the crown cavity into a similar series of crown compartments J', J², J³, J⁴, each of which is connected to corresponding side cavities H', H², etc. As shown in Fig. 2, the division walls K are provided with expansion joints K' to allow relative expansion and contraction of adjoining arch sections under varying thermal conditions. Each of the side compartments H', H², etc. are connected at their lower ends to a horizontal distributing flue M² by passages M³. The flues M² open to the external atmosphere through one or more air inlet ports M controlled by dampers M', the number and size of the ports depending on the estimated amount of cooling medium required. Each of the corresponding crown compartments is connected with a vertical outlet pipe N mounted in the kiln crown adjacent the division wall at the inlet end of the compartment. Each pipe N opens into an air collector pipe or masonry flue N' extending longitudinally of the kiln above the kiln crown.

The cooling zone section b' is provided with a hollow arch formed by an inner arched wall P of panel brick, of carborundum or other material of high thermal conductivity, spaced from the inner face of the side wall B and kiln crown A' and mounted on the kiln benches C as heretofore described. Each of the side wall cavities in this section of the cooling zone is divided into a plurality of relatively narrow vertical channels Q by projecting portions B' of the kiln side walls. The crown cavity Q' in this section of the kiln is similar to those in the section b² and connects the various side channels Q with an inlet pipe Q² mounted in the kiln crown. The channels Q open at their lower ends into the longitudinally extending ducts R located below the side walls. The ducts R extend below the heating zone of the kiln and are connected to the various groups of fuel burners in a manner well known in the art.

The collecting pipe N', which extends above the cooling zone section b², is closed at its end adjacent the exit end of the kiln and its opposite end connected to the inlet side of a cooling fan S driven by an electric motor S' and mounted on or at one side of the kiln crown. The amount of the cooling medium draw into the fan through the collector

pipe N' is controlled by a damper S² positioned in the pipe N' adjacent the fan. The fan discharge is connected to a main discharge pipe T to which the inlet pipe Q² leading to the crown cavity Q' in the cooling zone section b' is connected. The fan discharge pipe is also provided with branch pipes T' and T², the pipe T' opening to the atmosphere or preferably to a drying or preheating chamber adjacent to or forming a part of the kiln illustrated, and the pipe T² being connected as shown to one or more nozzles T³ immediately beneath the crown portion of the wall G and through which the air is discharged into the kiln chamber to off-set the tendency of the hot gases in the kiln chamber to drift toward the exit end of the kiln chamber. The air discharged into the kiln chamber at this point may travel longitudinally of the kiln chamber to the entrance end thereof or may be withdrawn into the cooling zone cavities through port T⁵ in the wall G, as illustrated diagrammatically in Fig. 1. Each of the pipes T, T' and T² connected to the fan discharge is provided with a damper T⁴, whereby the amount of air passed therethrough may be regulated.

In operation the goods carrying cars are periodically inserted into the kiln one at a time and as each car is thus inserted, the train of cars filling the kiln chamber is moved forward a car length, a car being removed from the cooling zone of the kiln each time a car is inserted at the entrance end of the kiln. As a car moves slowly through the heating zone of the kiln, the goods are gradually heated up to their maximum temperature and as each car passes through the cooling zone, the sensible heat in the goods and in the car is to a large extent transferred to the adjacent walls P and G, from which the heat is taken up by the large volume of low temperature circulating cooling air passing upwardly through the cavity compartments H', etc., formed at the sides of the goods pathway. The air heated in each compartment passes along through the corresponding crown compartment where more heat is absorbed and through the outlet pipe N to the hot air collecting pipe N'. The air from each compartment is thus drawn to the air fan S. In normal operation only a small portion of the air necessary for cooling purposes is utilized for combustion, the fan discharging this portion of the air through the pipe Q² to the crown cavity Q'. The air for combustion is further heated to a relatively high temperature while passing horizontally through the crown cavity Q' and downwardly through the narrow side channels Q to the underground ducts R leading to the fuel burners. The main body of cooling air passing to the fan is discharged to the pipes T' and T² and utilized for the purposes described.

With a kiln constructed and operating as

heretofore described, the pressure of the cooling air in the cooling zone section b^2 is below atmospheric pressure, while the pressure of the air for combustion passing downwardly through the cooling zone section b' is advantageously above atmospheric pressure. The kiln chamber temperature decreases at a relatively rapid rate in the successive cooling zone sections due to the large volume of cooling air in circulation and the external 10 radiation of the side walls. The cooling zone temperatures can be closely regulated by varying the speed of the fan and/or the effective inlet port area.

15 The heated air for combustion delivered to the ducts R may be at a temperature above 500° C. By my invention the fan is advantageously positioned at a point where the temperature of the cooling air handled is well below the allowable temperature for 20 safely operating the fan, but where it can deliver air for combustion to the ducts R at the desired temperature and pressure and without an excessive expenditure of power.

25 While the arrangement of separate crown cavity sections with individual air outlets is advantageous in installations where careful regulation of the cooling zone temperatures is necessary, the division walls K in the 30 crown cavities may in some installations be dispensed with and all the cooling air delivered to the fan S at one point in the continuous crown cavity, the amount of air entering each wall section being regulated by 35 the dampers M'.

While in accordance with the provisions of the statutes, I have illustrated and described the best form of embodiment of my invention now known to me, it will be apparent to 40 those skilled in the art that changes may be made in the form of the apparatus disclosed without departing from the spirit of my invention as set forth in the appended claims and that in some cases certain features of my 45 invention may be used to advantage without a corresponding use of other features.

Having now described my invention what I claim as new and desire to secure by Letters Patent, is:—

50 1. In a tunnel kiln comprising a heating zone and a cooling zone with a goods passageway therethrough, the improvement which comprises a fluid channel adjacent said goods passageway in one portion of the cooling zone, a second cooling zone portion between said first mentioned portion and said heating zone and means for circulating a cooling medium through said channel in said first mentioned portion at a pressure below atmospheric and delivering said medium to said second mentioned portion at a pressure above atmospheric.

60 2. In a tunnel kiln comprising a heating zone and a cooling zone with a goods passageway therethrough, the improvement

which comprises a fluid channel adjacent said goods passageway one portion of the cooling zone, a second cooling zone portion between said first mentioned portion and said heating zone, and means for circulating air 70 for combustion through said channel in said first mentioned portion at a pressure below atmospheric and delivering said air to said second mentioned portion at a pressure above atmospheric. 75

3. In a tunnel kiln comprising a heating zone and a cooling zone with a goods passageway therethrough, the improvement which comprises means dividing the cooling zone into a series of end to end sections, a fluid channel in one of the side walls of one cooling zone section for the passage of cooling air therethrough, a fluid channel in the side wall of a section between said first mentioned section and said heating zone, and means for drawing air through said first mentioned channel and delivering said air under pressure to said last mentioned channel. 80

4. In a tunnel kiln comprising a heating zone and a subsequent cooling zone with a goods passageway therethrough, the improvement which comprises means for heating air for combustion in said cooling zone and delivering said heated air to said heating zone, 90 said means comprising a circulating fan located at a point externally of said kiln and adjacent said heating and cooling zones. 95

5. In a tunnel kiln comprising a heating zone and a subsequent cooling zone with a goods passageway therethrough, the improvement which comprises means dividing said cooling zone into adjacent high and low temperature sections and a circulating fan located intermediate said high and low temperature sections for circulating a cooling medium therethrough. 100

6. A tunnel kiln having a heating zone, a cooling zone, a goods passageway through said zones, a plurality of separate compartments in the side walls of said cooling zone, conduits connecting said compartments, a circulating fan arranged in said conduit connections for circulating a cooling medium therethrough, conduits connected to the outlet of said fan, and means for separately delivering regulable portions of said cooling medium to the goods passageway in said cooling zone and to the fuel burners in said heating zone. 110

7. A tunnel kiln comprising a cooling zone, a goods passageway through said zone, a series of separate hollow arches is said zone partially enclosing said passageway, a conduit connecting said arches, and means for circulating a cooling medium upwardly through some of said arches and downwardly through another of said arches. 115

8. The method of operating a continuous tunnel kiln having a cooling zone which con- 120

sists in passing a cooling fluid at a sub-atmospheric pressure through one portion of said cooling zone and delivering said cooling fluid to another portion of said cooling zone at a super-atmospheric pressure.

5 9. The method of operating a continuous tunnel kiln having a heating zone and a cooling zone which consists in circulating air for combustion at a sub-atmospheric pressure through one portion of said cooling zone and delivering said air in another portion of said cooling zone in which it is heated to a predetermined final temperature at a super-atmospheric pressure.

10 15. Signed at Sedgley, near Dudley, Worcester, Great Britain, this day of July 9th A. D. 1929.
